UNITED STATES PATENT OFFICE.

FRANK B. WHEAT, OF LOS ANGELES, CALIFORNIA.

SECTIONAL PARTITION OR PANEL STRUCTURE.

Application filed August 1, 1927 Serial No. 209,977.

This invention relates to partition or panel structures which are made up of a plurality of sections whose meeting edges are adapted to be concealed by pilasters, said sections and pilasters being so interlocked as to permit the same to not only be readily assembled but to also permit them to be disassembled. For this reason the partition or panel structure of the present invention might be termed a portable one.

One object of the present invention is to provide a sectional partition wherein means are provided for holding the panels or partition sections in alinement preparatory to the pilasters being placed against and locked to said sections. In so far as the maintenance of the panel sections in alinement is concerned, the present invention is an improvement on applicant's prior Patents No. 20 1,626,259, granted April 26, 1927.

In that patent it was sought to provide means which both locked the pilasters to the sections as well as the sections to each other while the invention in the present case, if described specifically, consists in providing those locking means with additional means for holding the sections in alinement with each other preparatory to the pilasters being locked in place against the sections.

30 In the accompanying drawing,

Figure 1 is an elevational view, partly in section, of a partition embodying the present invention.

Fig. 2 is a vertical sectional view through the partition showing the pilasters locked in place.

Fig. 3 is a horizontal sectional view through a portion only of a partition illustrating the meeting edges of two partition sections with pilasters locked in position over the joint between the same.

Fig. 4 is a side elevation of a portion of one of the sections.

Figs. 5 and 6 are detail views of the locking element adapted to be carried by the panel sections.

The partition may, of course, be of any desired length, but, in the present instance, it is only necessary to describe two juxtaposed sections in order to fully disclose the invention. In the accompanying drawings the joint formed between the meeting edges of two juxtaposed sections 10 is adapted to be concealed by a pilaster 11 overlying the joint at one side of the partition and by the pilaster 11^a on the opposite side. The lock-

ing means for securing the pilasters to the two sections 10 are also utilized for locking the two partition sections themselves together. In the present instance, this is accomplished by having locking elements secured to the meeting edges of each partition section 10 adapted to project into recessed portions in the pilasters and there interlock with locking elements on said pilasters whereby the interlocked locking elements on the sections and pilasters firmly secure the pilasters to the sections, and those portions of the locking elements on the sections which project into the recessed portions of the pilasters serve to prevent movement of the two sections 10 away from each other.

In the preferred form the locking elements on the edges of the sections 10 consist of a plate 12 secured to the sections 10, said plates being formed with hook members 13 serving as latches adapted to engage behind locking plates 14 on the pilasters, the pilasters being recessed adjacent each interlocking plate so as to permit the hook portions 13 of the plates 12 to engage behind said locking plates 14. When the partition is being assembled the two sections 10 are properly placed together and a pilaster is then positioned over the joint formed at the meeting edges of said sections, so that the hook members 13 of plates 12 engage behind the locking plates 14 on said pilaster. Assuming the pilaster 11 shown in Fig. 2 to be the first one to be assembled, pilaster 11 is then placed against the opposite side of the partition with its locking plates 14 slightly above the protruding hook members 13. The pilaster is then lowered so that said hook members engage behind the locking plates 14 thereon. In this way the two pilasters are firmly locked to the partition section and by reason of the protruding hooked ends 13 of members 12 projecting into the recessed portions of the pilasters the partition sections themselves will also be firmly locked together. In this connection, it will be understood that each of the meeting edges of the two panel sections carry similar locking members 12, the members on one section being positioned intermediate the members 12 on the other section vertically of the joint formed by the two sections. In other words, alternate locking members 12 are on the edge of one section 10 and the other alternate locking members 12 are on the

edge of the other section 10, the total number of locking members on the two sections corresponding to the number of locking plates 14 on one pilaster.

6 It will be understood, of course, that the present invention is also adapted for use in panels as well as in partitions. It can also be used for counterfronts or for panel wainscoting or in other similar instances 10 where a pilaster is used only on one side. Where such use is made of the invention the locking plate 14 is screwed or attached to the concealed face of each two juxtaposed panel sections so as to engage the hook 15 members 13 at one end of the locking members 12 carried by said panel sections.

In either instance the pilaster or pilasters will be securely locked in place and by reason of the fact that each of the two meeting 20 edges carry locking members 12, the sections themselves will be firmly locked together. Other advantages consist in the lower costs of production of the locking elements and not only are such locking elements of plain and strong construction but they are also so arranged on the panel or partition sections and on the pilasters that they cannot very easily be damaged prior 25 to assembly.

30 After the two panel sections have been lined up with one another and before the pilaster is attached, it is, of course, desirable that they remain in alinement until locked in place by the pilaster. This may be accomplished by means of metal clips 35 engaging in recesses 15 in the side faces of each two juxtaposed panels. Such clips need not be formed separately from the locking plates 12, as the latter can be provided with offset portions 16 whose extremities are turned inward as at 17. These in-turned end portions 17 engage in recesses 12. Preferably portions 16 of each plate 12 extend 40 in opposite directions so as to engage in the panels on opposite sides of the partition. In this way the same plate 12 has three functions, i. e., it cooperates with plate 14 to lock the pilaster to the sections; it cooperates with recesses in the pilasters 50 to lock the sections together; and it cooperates with the recesses in the panels to hold the latter in alinement with one another until the pilasters are locked in place. The particular form of plate 12 illustrated 55 may, of course, be varied and the same results obtained and for this reason the following claims are not to be limited to any specific form of plate except where limitations are expressly recited.

60 I claim:

1. A sectional partition or panel structure comprising two juxtaposed sections, a pilaster separable from the sections, and overlying the joint between the same, means for securing said pilaster to the sections, and

means for holding said sections in alinement preparatory to placement of the pilaster against said sections.

2. A sectional partition or panel structure comprising two juxtaposed sections, a pilaster separable from the sections, and overlying the joint between the same, means for securing said pilaster to the sections, means for locking said two sections together, and means for holding said sections in alinement 70 preparatory to placement of the pilaster against said sections.

3. A sectional partition or panel structure comprising two juxtaposed sections, a pilaster separable from the sections, and overlying the joint between the same, and means for securing said pilaster to said sections, said means having formed integrally therewith additional means for alining said sections preparatory to placement of the pilaster 80 against the sections.

4. A sectional partition or panel structure comprising two juxtaposed sections, a pilaster separable from the sections and overlying the joint between the same at each side of the partition, and means for securing said pilasters to the sections, said means serving as a lock for securing said two sections together and for holding the sections 90 in alinement with each other preparatory to placement of the pilasters against the same.

5. A sectional partition or panel structure comprising two juxtaposed sections, a pilaster separable from the sections and overlying the joint between the same at opposite 100 sides of the partition, and cooperating locking elements on said pilasters and sections for locking the pilasters to the sections, the locking elements on one of said members 105 constituting means for holding the sections in alinement preparatory to placement of the pilasters against the sections.

6. A sectional partition or panel structure comprising two juxtaposed sections, a pilaster separable from the sections and overlying the joint between the same, catches 110 on said pilaster and cooperating latches on said sections for locking the pilaster to said sections, said latches having means formed integrally therewith for holding the two 115 juxtaposed sections in alinement.

7. A sectional partition or panel structure comprising two juxtaposed sections, a pilaster separable from the sections and overlying the joint between the same, catches 120 on said pilaster, cooperating latches on said sections for locking said pilaster to the sections, and means for holding the sections in alinement preparatory to placement of the pilaster against said sections.

8. A sectional partition or panel structure comprising two juxtaposed sections, a pilaster separable from the sections and overlying the joint between the same, metallic 125

plates constituting catches on said pilaster, and plates on said sections constituting latches adapted to cooperate with such catches for locking the pilaster to said sections, and means formed on said plates on the sections for holding said sections in alinement during placement of the pilaster against the sections.

9. A sectional partition or panel structure comprising two juxtaposed sections, a separable pilaster overlying the joint between the same, clips each engaging both of said sections and holding the same in alinement with one another, locking elements on the pilaster, and locking elements formed integrally with said clips and engaging the locking elements on the pilaster to lock the latter to the sections.

10. A sectional partition or panel structure comprising two juxtaposed sections each

having recesses in its opposite faces, a pilaster separable from the sections and overlying the joint between the same, cooperating locking elements on the sections and pilaster for locking the pilaster to the sections, and means on the locking elements on said sections for engaging in recesses in both sections and holding said sections in alinement.

11. A sectional partition or panel structure comprising two juxtaposed sections each having recesses in its opposite faces, a separable pilaster overlying the joint between the two sections, a plate on each section, locking elements on the pilaster, projections on the plates engageable with said locking elements for securing the pilaster to the sections, and projections on said plates engageable in the recesses in the sections for holding the latter in alinement.

FRANK B. WHEAT.
